C. E. Elliott,

Attorney
Plummer & Dyer.

UNITED STATES PATENT OFFICE.

CHARLES ELVIN ELLIOTT, OF WELLSBURG, WEST VIRGINIA.

RAIL JOINT.

Application filed May 11, 1925. Serial No. 29,440.

To all whom it may concern:

Be it known that I, CHARLES ELVIN ELLIOTT, a citizen of the United States, residing at Wellsburg, in the county of Brooke and State of West Virginia, have invented certain new and useful Improvements in a Rail Joint, of which the following is a specification.

This invention relates to an improved rail joint, and it has particular reference to a structure which has been designed especially to obviate the necessity of employing bolts.

Briefly, the invention comprises a novel rail chair, in which the webs of abutting rails are seated, there being novel coating means between the webs and the side walls of the chair for affording a good joint which is maintained simply by the use of the ordinary spikes.

The advantage and efficiency of a structure of this kind will become more readily apparent from the following description and drawing.

In the accompanying drawing forming a part of this application and in which like numerals are employed to designate like parts throughout the same:

Figure 1 is a side view showing a portion of a rail road track wherein the improved joint structure is incorporated, but practically concealed.

Figure 2 is a view showing one-half of the rail chair removed to disclose the specific construction of the joint.

Figure 3 is a perspective view of one end of a rail as modified to render it usable in the improved chair.

Figure 4 is a detail perspective view of the chair.

In the drawing, the reference character 1 is employed to designate the improved rail chair. By directing attention more particularly to Figure 4, it will be seen that this chair comprises a pair of spaced parallel side plates 2, corresponding to the ordinary fish plates, there being outwardly extending base flanges 3, at the bottoms thereof. These flanges are shaped to accommodate rail spikes 4. In the present instance the plates

2 are spaced apart a distance to receive the webs of the cooperating rails 5, and they are maintained in this relation by a plurality of longitudinally spaced cross pieces 6 acting as bridges. These bridges are of a cross sectional shape and area indicated in Fig-

ure 2, it being noted that they are disposed between the upper and lower edges of the side plates 2.

Each rail being of the same construction, a description of one will suffice for both. To this end it will be seen that the rail comprises the usual head or ball 7, a web 8 and a base flange 9. In this connection it will be noticed that the base flange terminates in inwardly spaced relation from the free end of the ball, thus allowing the web to project beyond it. The web is fashioned to provide a depending locking tongue 10 adjacent its free end, this tongue being provided with oppositely extending retaining lugs 11. The web is also provided with a supplemental lug 12 cooperating with the first named lugs. At this time, attention is directed to the fact that the bridges 6 are spaced apart distances which allow the passage of the lugs 11 and 12 between them so that the lugs may assume the cooperative relation indicated in Figure 2.

In practice, the rail chair is placed upon the adjacent ties and spans the space therebetween as clearly illustrated in the drawings, the abutting end sections of the rails are then dropped down into the chair between the vertical side plates either simultaneously or successively. It is of course understood that when the rail sections are disposed within the chair, the depending tongues and the laterally extending lugs formed on the lower ends thereof will move vertically between the spaced bridges 6. After the rail sections have been lowered into the chair so that the upper edges of the laterally extending lugs are disposed below the bottom faces of the bridges, the chair is then moved bodily across the ties toward the left hand direction and this will cause the bridges to be brought into engagement with certain of the laterally extending lugs 11 and 12 respectively. In this manner, the abutting end sections of the rails will be anchored in the rail chair and the position of the parts when in their locked relation is clearly illustrated in Figure 2 of the drawing. It will thus be impossible for the rail sections to be raised upwardly out of the rail chair. Now the chair is spiked in place, and a spike is located between the flanges 9 and 3 at the right as indicated in Figure 1 to maintain the last named rail section in a set position. It is thus obvious that with

this arrangement it is impossible for the rail end to be pulled out of the chair, and a sturdy and positive joint is provided, the same obviating the necessity of employing bolts and nuts as is ordinarily necessary.

It is thought that by considering the description in connection with the drawings, persons familiar with structures of this class will be able to obtain a clear understanding of the invention. Therefore, a more lengthy description is thought unnecessary.

While the preferred embodiment of the invention has been shown and described, it is to be understood that minor changes coming within the field of invention claimed may be resorted to if desired.

Having thus described the invention, what I claim as new and desire to secure by Letters Patent is:—

1. In a rail joint of the class described, a rail chair comprising spaced parallel vertical side plates provided with outwardly extending base flanges, longitudinally spaced connecting bridges between the side plates; a pair of complementary rail sections having extended web and ball portions, the extended web portions being fashioned to pro-

vide depending tongues, laterally extending locking lugs on the free ends of the tongues, said locking lugs being slidably cooperative with the aforementioned bridges to detachably secure the rail sections in said chair.

2. In a rail joint of the class described, a rail chair comprising spaced parallel vertical side plates provided with outwardly extending base flanges, longitudinally spaced connecting bridges between the plates, said bridges being spaced from the upper and lower edges respectively of the plates, a pair of complementary rail sections having extended web and ball portions, the extended webs being provided with cut out portions whereby laterally disposed locking lugs are formed, the space between the lugs being adapted to accommodate the bridges when the rail sections are placed downwardly within the rail chair, said laterally extending locking lugs being adapted for slidable engagement with the bottom faces of certain of said bridges whereby the rail sections are locked against vertical movement within the rail chair.

In testimony whereof I affix my signature.

CHARLES ELVIN ELLIOTT.
